UNITED STATES PATENT OFFICE

ROGER M. HILL, OF WASHINGTON, DISTRICT OF COLUMBIA

RADIANT AND REFLECTOR ADJUSTING MECHANISM FOR PROJECTION APPARATUS

Application filed July 16, 1926. Serial No. 123,002.

This invention relates to stereopticons, spotlights and other forms of projection apparatus, more especially it is directed to a lamp house mechanism for effecting the various adjustments of radiant and reflector incidental to focusing.

One object of this invention is to provide a device permitting the multi-focusing adjustments of radiant and reflector as described in my Patent No. 1,631,529, issued June 7, 1927, but eliminating to a large extent the numerous castings, controls and associated parts heretofore required for these movements.

Another object of this invention is to provide a radiant and reflector adjusting mechanism including swivelly mounted turrets manually rotatable in one direction and automatically operable in the other.

Other objects of this invention are to simplify the operation of adjusting radiant and reflector by arranging their controls in an easily remembered and predetermined order; provision of means to relieve the rack and pinion mechanism of the weight of the turret and to furnish an apparatus having interchangeable parts to simplify repairs and reduce cost of maintenance.

With these and other objects in view this invention consists in certain novel details of construction, combination and arrangement of parts to be more specifically set forth and claimed.

Briefly stated this invention embodies telescopically associated, swivelly mounted, axially aligned upper and lower radiant and reflector supporting turrets, rotatably positioned upon a longitudinally operable carriage. Control rods operably connected with the turrets, carriage and reflector to permit the requisite adjustment thereof and automatic means in connection with certain of the control rods functioning to automatically return the turrets to initial position.

Referring more particularly to the accompanying drawings in which corresponding parts are indicated by similar reference characters:

Fig. 1 is a perspective view of the assembled fixture.

Fig. 2 is a side elevation of the assembled fixture, showing a lamp housing and condenser holder in dotted outline.

Fig. 3 is a sectional view of the lower rack support, upper and lower racks, elevating pinions, upper and lower turrets and longitudinal adjusting means for the reflector.

Fig. 4 is a rear elevation of the assembled fixture.

Fig. 5 is a fragmentary sectional top plan view taken along the lines 2—2 of Fig. 2, and

Fig. 6 is a fragmentary perspective of the lower rack support, rack, lower turret and lower arcuate adjusting rod.

In many of the familiar types of adjusting fixtures used in projection apparatus that utilize the incandescent light instead of the arc, the adjustments of the reflector and the luminant are so complex that it makes it difficult to adjust the same to their proper relative positions for focusing.

It is therefore the aim and purpose of this invention to provide an adjusting means which will be extremely simple in construction, having few parts, some of which can be made interchangeable, and thus not only reduce the cost of manufacture and replacement, but also to provide an apparatus which is easily operated.

In the illustrated embodiment characterizing this invention, a carriage consisting of a base (1) is slidably mounted upon the tracks (2) by means of three runners (3) which project from opposite sides of the base. These tracks are mounted on the base of the lamp house (4), being held thereto by the projecting lugs (5) and permit of a longitudinal movement of the carriage thereon.

Centrally located at the rear of the carriage base (1) is a perpendicularly projecting lug (6) tapped for threaded engagement with the screw (7) formed at the inner end of control rod (8). The control rod is mounted within a circularly drilled opening in a lug (9) which projects from the base of the lamp house. The lug (9) is drilled for the reception of a screw (10) the end of which fits into a circular groove (11) cut in the control rod (8), thus allowing the control rod

to rotate within the lug, but preventing the longitudinal movement thereof, so that by rotation of the control rod (8) its threaded end (7) produces a longitudinal movement of the carriage.

Centrally located in respect to the base (1) of the carriage and projecting perpendicularly thereto is a cylindrical bearing (12). Near the upper extremity of this bearing (12) 10 are two cylindrical lugs (13) and (14) which project rearwardly, their central axes being parallel to the plane of the base. These lugs are joined to each other and to the bearing and base by suitable reinforcing webs.

15 One of these lugs (13) is tapped to receive the threaded end (15) of the control rod (16), and the other lug (14) is circularly drilled to receive the control rod (17) which is cut at its end to form a pinion (18), the function of which will hereinafter be described. The pinion (18) of the control rod (17) is held in position within the lug (14) by means of the machine screw (19), the end of which projects into a circular groove (20) cut in the 25 control rod (17), as shown in Fig. 3.

Rigidly attached at the front of the cylindrical bearing (12) by machine screws (21) 30 is a curved leaf spring (22) which bends backward, its free end terminating a short distance beyond the lug (13). The upper end of the cylindrical bearing (12) is tapered or stepped down at (23) as shown in Figs. 3 and 6, to a smaller diameter for the reception of the coil spring (24) the purpose of which 35 will be hereinafter described.

The cylindrical bearing (12) forms a mounting for the lower turret (25). This turret is mounted upon a shaft (26) at the lower end of which is cut a circular rack (27). 40 The shaft (26) of the lower turret (25) is slidably mounted within the cylindrical bearing (12), the teeth of the rack (27) intermeshing with those of the pinion (18) cut on the end of the control rod (17).

45 Thus rotation of the control rod (17) raises and lowers the shaft (26) within the cylindrical bearing (12). The upper end of shaft (26) is shaped to form a turret (25) which consists of a cylindrical base (28), having 50 near its lower end a laterally projecting arm (29), terminating in a cylindrical lug (30). This lug (30) is drilled to receive the circular rod (31), which projects therefrom in a perpendicular direction, its central axis 55 being parallel to that of the shaft (26), said rod passing downward between the free end of leaf spring (22) and the end of control rod (16).

Near the lower end of the cylindrical body 60 (28), of turret (25) and formed tangential thereto is a bracket supporting base (32), to which is attached the incandescent lamp bracket (33). This bracket (33) is insulated from the base (32) by means of the insulating 65 plate (34) and attached to said base (32) by

means of the machine screws (35), as is fully described in my Patent No. 1,631,529, issued June 7, 1927.

The lower end of the cylindrical body (28) 70 of the turret (25) is stepped down to a cylinder of smaller diameter at (26), for the reception of the coil spring (24) which surrounds the shaft (26), and is held under compression between the cylindrical bearing (12) and the turret (25). 75

At the upper end of the cylindrical body (28) 80 of the lower turret (25) are formed cylindrical lugs (37), and (38) which project rearwardly, their central axes being parallel to the plane of the base. These lugs are joined to each other and to the turret (25) by suitable reinforcing webs.

85 One of these lugs (37) is tapped to receive the threaded end (39) of the control rod (40), the other lug (38) is circularly drilled to receive the control rod (41) which is cut at its end to form a pinion (42), the function of which will be hereinafter described. The pinion (42) of the control rod (41) is held in position within the lug by means of the machine screw (43), the end of which projects into the circular groove (44) cut in the control rod (41), as shown in Fig. 3.

Rigidly attached at the front of the cylindrical body (28) 90 of the lower turret (25) by machine screws (45), is a curved leaf spring (46) which bends backward, its free end terminating a short distance beyond the lug (37). The upper end of the cylindrical body (28) 95 of the lower turret (25) is stepped down at (47), as shown in Fig. 3, to a smaller diameter for the reception of the coil spring (48), the purpose of which will hereinafter be described.

The cylindrical body of the lower turret 100 (25) is internally drilled for the reception of the shaft (49) of the upper turret (50) which is slidably mounted therein. On the lower end of shaft (49) is cut a circular rack (51) which intermeshes with the teeth 105 of the pinion (42) cut on the end of the control rod (41). Thus rotation of the rod (41) raises and lowers the shaft (49) within the lower turret (25).

The upper end of shaft (49) is shaped to 110 form the upper turret (50) which consists of a flat cylindrical base (52) having a laterally projecting arm (53), terminating in a cylindrical lug (54). This lug (54) is 115 drilled to receive the circular rod (55), which projects therefrom in a perpendicular direction, its central axis being parallel to that of the shaft (49), said rod passing downward between the free end of leaf spring (46) and the end of control rod (39). 120

125 Mounted on the cylindrical base (52) of the turret (50) and at right angles to the same, is a split sleeve (56) which may be closed by the set screw (57). Directly beneath this split sleeve is a rearwardly ex- 130

tending arm (58), at the extremity of which terminates in a cylindrical bearing (59), adapted to rotatably receive the control rod (60). The central axis of this bearing (59)

5 corresponds with that of the split sleeve (56) which is positioned in front of it. The split sleeve (56) is drilled to slidably receive a shaft (61) from which projects a lug (61'), said lug preventing the shaft from turning 10 within the sleeve (56).

Shaft (61) is tapped internally for the reception of a screw (62) cut at the end of the control rod (60). The control rod (60) has a circular groove (63) cut in it for the 15 reception of the machine screw (67), which prevents the rod (60) from having a longitudinal movement within the bearing (59), but permits the rotation of the same, thus effecting longitudinal movement of the shaft 20 (61) within the split sleeve (56). At the front of this shaft is a flange (65) and to this flange is connected a circular disc (66) to which are attached clips (67). The whole combination forming a holder for the reflector (68).

As shown in Fig. 1 all of the control rods project from the rear of the lamp house (4) and are equipped with suitable thumb wheels (69), (70), (71), (72), (73), and (74). 30 These thumb wheels are therefore shielded from the heat of the luminant which greatly aids the operator in making necessary adjustments while the projector is in operation.

Besides the rotary movement which is imparted to the control rods, the lower control rods (16) and (17), have a horizontal movement, since they are carried back and forth by the carriage, and the upper control rods (60), (40) and (41) have not only this additional horizontal movement but also a vertical and arcuate movement. It is therefore necessary to provide movable shields (75) and (76) on the rear wall of the lamp house through which these rods project. The 45 shield (75) is drilled at (77) and (78) for the reception of rods (40) and (41) and has in addition to this a slot (79) for the projection of rod (60) which also passes through a small shield (76) superimposed upon the 50 shield (75). It is necessary to use this superimposed shield since the relative position of the rods (40), (41) and (60) varies with the elevation of the upper turret (50). The coil spring (80) on control rod (60) presses 55 against the shield (76) and thus holds both shields against the rear wall of the lamp house.

The operation of the device will now be described. The upper turret (50), the lower 60 turret (25) and the cylindrical bearing (12), which are mounted on the carriage are all telescopically fitted, one within the other, so that any horizontal movement of the carriage (1) moves both the lamp and the reflector in unison. Manipulation of the con-

trol rod (8) therefore advances or retards the entire lighting system within the lamp house either towards or away from the condenser.

Since the upper turret is mounted within the lower, and held in any set position by means of the pinion (18), elevation or lowering of the lower turret (25) is transmitted to the upper turret (50) and therefore both the lamp and the reflector are raised or lowered 70 vertically in unison by manipulation of the control rod (17).

It will be noted from the construction that the angular relationship between the upper and lower turret is varied by means of the 80 control rod (40). This control rod in conjunction with the leaf spring (46) provides a means for locking the upper and lower turret at any desired angularity.

When the lower control rod (16) is turned the lower turret (25) is moved arcuately carrying with it the upper turret (50). Any independent movement of the upper turret (50) in an arcuate direction is effected by operation of the control rod (40) and independent vertical movement of the upper turret (50) is effected by operation of the control rod (41).

It will be seen that the three lower rods 85 (8), (16) and (17) control the movements of the lamp and reflector as a whole so that operation of any of these rods moves both the upper and lower turrets in unison, the relative positions of the lamp and reflector with respect to each other remaining unchanged.

The coil spring (24) which is positioned between the cylindrical bearing (12) and the lower turret (25) counter-balances the weight of the mechanism above it. The same applies for the coil spring (48) which is positioned between the lower and upper turrets. The leaf springs (46) and (22) hold the upper and lower turrets in such a position that the manipulation of the control rods (40) and (16) moves these turrets in an arcuate direction without lost motion.

The control rods are arranged in a uniform manner so that the thumb wheels at the rear are conveniently located for the operator. Operation of the extreme lower wheel (74) controls the horizontal movement of the lamp and the reflector in unison. The extreme upper wheel (69) controls the horizontal independent movement of the reflector. The centrally located wheels at the left control vertical movements; the lower (72) raises or lowers both the lamp and the reflector alone. The centrally located wheels at the right control the arcuate movements; the lower (73) controls the movements of both the lamp and the reflector, and the upper (71) controls the independent movement of the reflector.

From the foregoing the extreme simplicity of the construction and ease of operation is 130

evident. Interchangeability of parts, the elimination of back lash in the movements of the lamp and reflector and orderly and symmetrical arrangement of the control wheels 5 and the many other new features embodied in this invention are all decided improvements over the mechanisms now in use.

Although in the foregoing certain elements 10 have been described as best adapted to perform the functions allotted to them, nevertheless it is to be understood that various minor changes may be resorted to within the scope of the appended claims without departing from or sacrificing any of the principles of 15 the invention.

Having described my invention, what I claim as new and wish to secure by Letters Patent is:

1. In a projection apparatus, superimposed 20 turrets comprising a pair of axially aligned telescopically engaged shafts, a reflector on one and a radiant on the other, and means to impart independent arcuate movements to the shafts.

25 2. In a projection apparatus, superimposed turrets comprising axially aligned telescopically engaged shafts, said telescopic engagement being such as to permit relative swivel movement of the shaft, a reflector on one of 30 said shafts and a luminant on the other and means in connection with the respective shafts to effect their relative adjustment.

3. In a projection apparatus the combination 35 of a movable carriage, a pair of telescopically engaged, axially aligned, relatively adjustable and swivelly connected turrets mounted on said carriage and means to impart a relative rotary and vertical movement to the turrets, a reflector on one turret 40 and a radiant on the other.

4. In a projection apparatus the combination 45 of a longitudinally movable carriage, a pair of telescopically engaged, axially aligned relatively adjustable and swivelly connected turrets mounted on said carriage and means to impart a relative rotary and 50 vertical movement to the turrets and additional means to adjust the turrets as a unit, a reflector on one turret and a radiant on the other.

5. A projection apparatus comprising in 55 combination a base, cylindrical bearings positioned on the base, a pair of super-imposed telescopically engaged shafts, the lower end of one of the shafts being slidably positioned in said bearing, means in connection with the bearing and the lower end of the shaft there- 60 in to impart vertical movement to the latter, a reflector on one of the shafts and an illuminating fixture on the other, and means to 65 impart longitudinal movement to the base, said means comprising parallel guides, means carried by the base to slidably engage the guides, a control rod, the inner end of the

rod being in threaded engagement with the base.

6. In a projection apparatus the combination of upper and lower axially aligning and telescopically engaging shafts, means in 70 connection with the respective shafts to effect a relative sliding movement therebetween, a supporting base, means in connection with the base to rotatably journal the lower end of said lower shaft, a reflector adjustably mounted 75 on the upper and an illuminating fixture carried by the lower shaft.

7. A projection apparatus comprising in combination upper and lower axially aligned and telescopically engaged shafts, means for 80 actuating the upper relative to the lower shaft, said means comprising a rack and pinion mechanism, a bearing rotatably journaling the lower end of said lower shaft, a reflector adjustably mounted on the upper and 85 an illuminating fixture carried by the lower shaft.

8. A projection apparatus comprising in combination a pair of axially aligned tele- 90 scopic shafts, said shafts being intercon- nected for swivel movement, means coaxing with the upper shaft to swivel the latter in one direction, additional means in connection with said shaft to automatically restore said shaft to its initial position, means for verti- 95 cally adjusting the upper with respect to the lower shaft, a reflector affixed to said shaft, an illuminating fixture carried by the lower shaft and a bearing rotatably journaling the lower end of said lower shaft. 100

9. A projection apparatus comprising in combination a pair of axially aligning tele- 105 scopically engaging upper and lower shafts, a bearing rotatably journaling the lower end of said lower shaft, means in connection with said bearing to effect rotation of the shaft in one direction, additional means carried by the shaft to restore the latter to its initial position, a reflector affixed to the upper and an illuminating device secured to said lower 110 shaft. 115

10. In a projection apparatus, super-im- 120 posed turrets comprising a pair of rotatably connected and telescopically engaged shafts, a reflector on one and a radiant on the other and means in connection with the respective shafts to impart joint and independent ro- 125 tary movements thereto.

11. In a projection apparatus, super-im- 130 posed turrets comprising a pair of rotatably connected and telescopically engaged shafts, a reflector adjustably mounted on one of said shafts and a radiant on the other and means in connection with the respective shafts to impart joint and independent rotary move- 125 ments thereto.

12. In a projection apparatus, super-im- 130 posed turrets comprising a pair of rotatably connected and telescopically engaged shafts, a reflector longitudinally adjustable on one

of said shafts and a radiant carried by the other and means in connection with the respective shafts to impart joint and independent rotary movements thereto.

5 13. In a projection apparatus, super-imposed turrets comprising a pair of rotatably connected and slidably engaged shafts, a reflector on one and a radiant on the other, means in connection with the respective shafts to impart joint and independent rotary movements thereto and additional means in connection with said shafts to effect a lengthwise movement therebetween.

10 14. In a projection apparatus, super-imposed turrets comprising a pair of rotatably connected and slidably engaged shafts, said shafts being operable independently and in unison, a reflector on one and a radiant on the other, means to impart a rotary movement to said shafts as a unit and additional means in connection with said shafts to effect their lengthwise movement as a unit.

15 15. In a projection apparatus, super-imposed turrets comprising a pair of rotatably connected and slidably engaged shafts, a reflector on one and a radiant on the other, means in connection with the respective shafts to impart joint and independent rotary movement thereto, and additional means in connection with said shafts to effect a relative lengthwise movement therebetween.

20 16. In a projection apparatus, super-imposed turrets comprising a pair of rotatably connected and slidably engaged shafts, a reflector on one and a radiant on the other, means in connection with the respective shafts to impart joint and independent rotary movements thereto, additional means in connection with said shafts to effect a relative lengthwise movement therebetween and a spring encircling one of the shafts and disposed between said turrets, said spring contributing to the adjustment of the turrets when their shafts are relatively adjusted

25 45 lengthwise in one direction.

ROGER M. HILL.
